DOOR PULL

Robert James Elder, Sun Valley, Calif., assignor to
Northrop Architectural Systems, Los Angeles, Calif., a
corporation of California

Filed Aug. 20, 1965, Ser. No. 86,662

Term of patent 14 years

(Cl. D10—8)

Fig. 4

Fig. 5

Fig. 6

FIGURE 1 is a front perspective view of a door pull embodying my new design;

FIGURE 2 is a side elevational view thereof as seen from the left side of the front elevational view of FIGURE 5;

FIGURE 3 is a side elevational view thereof as seen from the right side of the front elevational view of FIGURE 5;

FIGURE 4 is a top plan view thereof;

FIGURE 5 is a front elevational view thereof; and

FIGURE 6 is a bottom plan view thereof.

I claim:

The ornamental design for a door pull, as shown and described.
